UNITED STATES PATENT OFFICE

WILLIAM G. OPEL, OF MCKEESPORT, PENNSYLVANIA

GEAR-WHEEL PULLER

Application filed February 25, 1930. Serial No. 431,209.

The present invention relates to wheel pulling devices and has for an important object thereof the provision of a puller which is adapted to facilitate the pulling of gears or 5 wheels from shafts or the like.

Another object of this invention is to provide a wheel puller which is so constructed that the outward movement of the levers or handles will force the shaft engaging member to move inwardly and coercively force the wheel gripping members to move outwardly.

The above and various other objects and advantages of this invention will in part be 15 described in and in part be understood from the following detailed description of the present preferred embodiment, the same being illustrated in the accompanying drawing wherein:—

Figure 1 is a detail fragmentary side elevation partly in section of a device constructed according to the preferred embodiment of this invention; and

Figure 2 is a sectional view taken on the line 2—2 of Figure 1.

Referring to the drawing, wherein like numerals of reference designate corresponding parts throughout the several views, the numeral 10 designates generally a frame 30 which is preferably constructed of metal so as to provide a rigid structure. The frame 10 comprises a pair of plate members 11 which are provided at the outer end portion thereof with an outstanding lug 12.

The plate members 11 are provided with a plurality of spaced apertures 13 for swingingly and adjustably receiving a pair of gear clamping or engaging members 14, the clamping members 14 being adjustably held on the frame 10 by a removable pin or bolt 15. The gear engaging or gripping members 14 are provided at the inner ends thereof with inwardly extending lugs 16 which are adapted to engage upon the inner face of the gear or wheel which it is desired to remove from a shaft.

A pair of handle members or levers 17 are swingingly mounted between the spaced lug members 12 as at 18, the inner portion of the

handle member 17 being preferably bifurcated as at 19.

A shaft engaging member 20 is slidably mounted at one end thereof in the frame 10, and in order to facilitate the sliding or horizontal movement of the shaft engaging member 20 a pair of anti-friction roller members 21 are rotatably mounted in the plate members 11 and engage against the opposite face portions of the shaft engaging member 20. The opposite face portions of the shaft engaging member 20 are provided with a plurality of teeth 22, and a pair of gear members 23 are rotatably mounted between the lug members 12 and are adapted for contacting engagement with the gear rack 22.

A swinging or rockable arm 24 is swingingly mounted at one end of the shaft 25 for the gear 23 and is adapted to extend outwardly of the lug members 12.

A link 26 is secured at one end to the bifurcated shank 19 of the levers 17 and at the opposite end is rockably secured as at 27 to the outer end portion of the rocking lever or arm 24.

A pawl member 28 is swingingly positioned on the arm 24 and is adapted for engagement with the teeth of the gear 23 so that when the levers or handles 17 are pulled outwardly, the arm 24 will be coercively rocked and the pawl 28 will rotate the gear member 23. A resilient spring or the like 29 is mounted on the arm 24 and is adapted to engage the pawl member 28 for holding the pawl member in contact with the gear 23.

The pawl member 28 is preferably mounted on a shaft 30 which extends outwardly of the arm 24 and is provided at the outer end portion thereof with a lever or outstanding member 31 so that when it is desired to release the pawl member from engagement with the gear 23, the lever 31 may be swung laterally of the frame and against the tension of the spring 29, the spring 29 being preferably constructed so that when the pawl 28 is swung out of engagement with the teeth of the gear 23, the pawl member will be held in inoperative position by the spring.

The gear rack 20 may be provided at the

inner end portion thereof with an axial pin or the like 32 which is preferably threadably mounted as at 33 on the inner end portion of the gear rack 20, the pin or centering member 32 being adapted to engage the shaft having the gear mounted thereon and preferably engages in the centering hole usually formed in a shaft.

In the use of this device, the clamping or gripping members 14 are preferably adjusted so as to engage about the periphery of the hub of the wheel or the periphery of the gear, and the lug members 16 are adapted to contact with the inner face of the hub or gear.

The centering member 32 is positioned on the outer end portion of the shaft whereupon the levers or operating members 17 may be pulled outwardly thereby coercively rocking the pawl member 28 and rotating the gear members 23 so as to force the gear rack 20 inwardly. The pressure exerted on the gear rack 20 will force the frame 10 outwardly thereby forcing the gear or wheel engaged between the clamping members 14 to move outwardly of the shaft.

The levers 17 may be rocked as desired and the resilient spring 29 will hold the pawl 28 into engagement with the teeth of the gear 23 so that the desired pulling pressure will be maintained on the gear engaging members 14.

It will, of course, be understood that various changes and modifications may be made in the details of construction and design of the above specifically described embodiment of the invention without departing from the spirit thereof, such changes and modifications being restricted only by the scope of the following claims.

What is claimed is:—

1. A puller of the character described comprising a frame, a pair of wheel gripping members adjustably mounted on the frame, a shaft engaging member slidably mounted in the frame, anti-friction means mounted in the frame and engaging said shaft engaging member, said shaft engaging member having a plurality of teeth on the opposite edge portions thereof, rotatable gears mounted in the frame and engaging said teeth of said shaft engaging member, and rockable pawl members carried by the frame and adapted for engagement with said rotatable gears for rotation thereof.

2. A puller of the character described comprising a frame, a plurality of clamping members adjustably mounted on the frame, a gear rack slidably mounted in the frame, anti-friction means carried by the frame and engaging said gear rack, a pair of gears rotatably mounted in the frame and engaging said gear rack, an outstanding arm swingingly mounted on the frame, means for rocking said arm, and a spring-pressed pawl carried by said arm and adapted for contacting

engagement with said gears whereby to rotate said gears coercively with the rocking movement of said arms.

3. A puller of the character described comprising a frame, a plurality of gear wheel gripping members adjustably mounted on said frame, a gear rack slidably mounted in said frame, said gear rack having teeth on the opposite edge portions thereof, a pair of gears rotatably mounted in said frame and engaging said gear rack upon the opposite edge portions thereof, a rockable arm mounted on said frame, a pair of opposed levers rockably mounted on said frame, link means connecting said levers with said rockable arms, and a spring-pressed pawl member rockably carried by said arms and adapted for engagement with said gears whereby to rotate said gears upon rocking movement of said arms.

4. A wheel puller of the character described comprising a frame, a plurality of wheel gripping members swingingly mounted on said frame, a gear rack slidably mounted in said frame, said gear rack having a plurality of teeth on the opposite edge portions thereof, anti-friction means mounted on said frame and engaging said gear rack, a plurality of gears rotatably mounted in said frame and engaging said gear rack, and releasable ratchet means rockably mounted on said frame and adapted to rotate said gears.

5. A wheel puller of the character described comprising a frame, a plurality of swinging jaw members adjustably mounted on said frame, a slideable gear rack mounted in said frame, a removable shaft engaging member mounted on said gear rack, and ratchet means rockably mounted in said frame and adapted to move said gear rack inwardly thereof.

6. A wheel puller of the character described comprising a frame, a plurality of jaw members adjustably and swingingly carried by said frame, a gear rack slidably mounted in said frame, a pair of gears rotatably mounted in said frame and engaging said gear rack, a pair of rockable arms mounted on said frame, a pair of rockable operating levers mounted on said frame, said levers having bifurcated inner end portions, a link member rockably mounted at one end in said bifurcated inner end portion of said operating levers and rockably secured at the opposite end to said arms and releasable spring-pressed pawl members mounted on said arms and adapted to engage said gears for rotation thereof upon swinging movement of said operating levers.

In testimony whereof I hereunto affix my signature.

WILLIAM G. OPEL.
